UNITED STATES PATENT OFFICE.

KARL GARAGULY, OF CHICAGO, ILLINOIS.

MUSICAL INSTRUMENT.

Application filed January 17, 1924. Serial No. 686,873.

This invention is directed to an improved musical instrument of the wood-wind type, but it has more particular reference to an instrument which belongs to the single reed 5 family.

Being a performer on instruments of the reed family, I have conceived certain defects in the intonation and quality of tone of both the conventional type of clarinettes 10 and saxophones. It is therefore my aim to produce an instrument resembling either of those specified, but which is built to overcome the tonal defects of the same, such as are readily noticeable to a skilled musician's 15 ears.

I also aim to produce a musical instrument which is perfectly proportioned to produce the proper and desirable tone-color, that is, to provide an instrument, the voice 20 of which will blend more perfectly with stringed instruments, one which is bold in relief against other instruments, yet is productive of a resonant and jovial tone.

More specifically speaking, I propose to 25 provide a musical instrument of the class under consideration which is productive of an exceedingly characteristic tone which is unmistakable for that of analogous instruments, this result being attained through the 30 use of a tube which is composed of wood and is equipped with a more or less conventional fingering system, but is of a length which has been discovered to dispose the tone holes at the exact points for securing perfect intonation in all registers, this result being 35 assured by the comparatively acutely tapered bore of the instrument and the exceedingly large bell on the outer end of the tubing.

40 Other features and advantages of the invention will become apparent from the following description.

In the drawing, the single figure represents a top plan or elevational view of an 45 instrument constructed in accordance with the invention, portions of the tubing being broken away and shown in section.

As before intimated, the improved instrument essentially comprises a comparatively long and externally tapered tube 50 which is generally referred to by the reference character 1. As is usual, this tube is composed of detachable telescopically connected sections 2 and 3 respectively. Here, 55 it may be conveniently emphasized that the entire tube is composed of wood similar to

that used in the construction of clarinettes. This is one distinguishing feature between the present instrument and the well known saxophone. As is usual, the mouthpiece 4 is 60 telescopically fitted onto the inner end of the section 2, and in practice, this mouthpiece will be adjustable longitudinally on the usual cork joint to permit variation of pitch. In addition to being externally tapered, the tube 1 is also internally tapered and this tapered is of a comparatively acute degree. In the conventional clarinette, the bore of the instrument is more or less uniform from end to end. Considerable experimentation with this design of tube has 65 proven that it is productive of excellent intonation in both registers or octaves of the instrument. 70

It may be conveniently set forth here that 75 the instrument shown is equipped with a fingering system quite similar to that used in conjunction with conventional and modern clarinettes. As this system of positioning of valves and tone-holes is well 80 known to those skilled in the art to which the invention relates, the detailed description of the system of fingering is thought unessential. It is to be emphasized however that owing to the increased length of 85 the tube 1 in comparison to the corresponding part of a clarinette and saxophone, the distances between toneholes is correspondingly increased, and it has been proven that by making the tubing of a specified 90 length, of the tapered degree mentioned and changing the distances of the tone-holes, perfect intonation is the result. To the skillful and musically trained ear, this is indeed an essential distinction and advan- 95 tage.

To assist in obtaining the characteristic tone qualities, greater volume and carrying power, I use a comparatively large bell 5 in conjunction with the tubing. As will be 100 observed, this bell is both externally and internally tapered and serves as a unique amplifier for the sound waves, especially of the lower register. Comparing the bell to that of the usual clarinette, it will be seen 105 that it is of considerably greater length and diameter.

I am well aware of the construction of conventional clarinettes and saxophones and a judge of tone quality. Specifically speaking, the voice of the proposed instrument is 110 more resonant than that of either the clari-

nette or saxophone and as before pointed out, the intonation is more perfect and hence the resultant tone is more enticing.

I claim:

- 5 1. A single reed musical instrument of the class described comprising a tube through which sound waves are adapted to pass, said tube being equipped at predetermined spaced points with tone holes, and a comparatively large bell on the outer end of said tube, the latter and said bell being internally and externally tapered from the inner end to the extremity of the outer end, and the continuity of the taper being unbroken from one end to the other.
- 10 2. A single reed musical instrument of the class described comprising a tube through which sound waves are adapted to

pass, said tube being provided at predetermined spaced points with tone holes, and being composed of two frusto-conical sections of substantially equal lengths joined together in a manner to render the internal and external tapered surfaces flush with each other, and an unusually large frusto-conical bell on the outer end of said tube, said bell being of a length substantially equal to the tube sections, and being of plane and substantially uniform taper from end to end, the tapered surfaces of said tube sections and bell meeting and being substantially continuous from one end of the instrument to the other.

In testimony whereof I have hereunto affixed my signature.

KARL GARAGULY.
